[57] CLAIM

The ornamental design for a chandelier, as shown and described.

DESCRIPTION

FIG. 1 is a perspective view of a chandelier, showing my new design;

FIG. 2 is a front elevational view of the chandelier, the rear elevational view being a mirror image;

FIG. 3 is a left side view of the chandelier, the right side view being identical;

FIG. 4 is a top plan view of the chandelier, and;

FIG. 5 is a bottom plan view of the chandelier.

The elements shown in broken lines are for illustrative purposes only.
